BY

ATTORNEY

UNITED STATES PATENT OFFICE

WALTER BILDSTEIN, OF BROOKLYN, NEW YORK

WINDOW AND SCREEN SECURER

Application filed June 20, 1930. Serial No. 462,551.

This invention relates to improvements in safety devices for securing windows and screens against being opened by unauthorized persons or children, and has for its principal object to provide a window and screen securer which is simple and inexpensive to manufacture yet durable and efficient in its operation, and a device which may be conveniently carried by travelers for securing 10 hotel room windows or the like against surreptitious entry.

Another object of my invention is the provision of a safety device which can readily be set up to hold half-screens in place so as 15 to allow a ventilation of a room without danger of children removing the screen and falling out of a window.

A further object of my invention is the provision of a safety device of this character 20 which may be telescoped so as to take up a comparatively small space when not in use.

These and other objects and advantages 25 of my invention will become more fully apparent as the description thereof proceeds and will then be specifically defined in the appended claims.

In the accompanying drawings forming a material part of this disclosure:

Fig. 1 is a front elevation of a window and screen securer constructed according to my invention.

Fig. 2 is a side elevation thereof.

Fig. 3 is a longitudinal section on line 3—3 of Figure 1.

As shown on the drawings, the window and screen securer constructed according to my invention comprises a metal tube 10 of a preferably square cross-section which, however, may have also any other shape, the upper 40 open end of which is adapted to receive a plug 11 adapted to be held in said tube or sleeve 10 by means of screws 12 or the like.

The upper part of the plug has integrally made therewith a head 13 laterally projecting beyond the outer limits of the tube, as at 45 14, and carrying at its upper face near its end a projecting member 15 adapted to engage in a socket 16 secured to the lower face of a window frame 17 by means of a screw 18 or the like.

The material of the tube 10 is slotted near its lower end, as at 19, and a band 20 is guided about its lower end and has formed at its inner ends oppositely disposed, perforated ears 21, 22. Through the perforations of these 55 ears extends a screw bolt or pin 23, one end of which is formed into a head 24, while its other end carries the sleeve 25 of a hand wheel 26.

Into the tube 10 telescopes from below a 60 hollow bar 27 of a cross-section identical with the cross-section of tube 10, and is guided therein through a slotted fibre collar or washer 28, while the upper end of bar 27 has formed therewith L-pieces or irons 29 for 65 limiting its outward movement by engagement with the collar 28. The lower end of bar 27 has attached thereto a base or foot 30 by means of screws 31 passing through a flange 32 of the base entering the lower end 70 of hollow bar 27. The base 30 is undercut to form a depending lip or tongue 33 adapted to engage the upper bar 34 of a window frame or the lock thereon. The lower end of foot 30 is equipped with a rubber cushion 35. 75

The operation of my device will be fully understood from the above description and by inspection of the drawings, and it will be clear that after securing the socket 16 to a window frame and engaging member 15 80 therein, the bar 27 is extended from tube 10 for the proper distance to suit the size of the window or distance between the upper end of a screen and upper window frame bar, and lip 33 is brought into engagement with the 85 upper edge of the lower sash or of the upper screen bar, and the band is drawn taut by means of the hand wheel to compress the lower slotted end of tube 10 about the bar 27 to lock bar and tube firmly in their relative adjusted positions.

The outward movement of bar 27 is limited by the engagement between the L-irons 29 and the fiber washer or collar 28, while the rubber cushion 35 will give the bar a firm 90 hold on a sash frame and prevent damaging of the same.

It will be understood that I have shown and described the preferred form of my invention only as one example of the many possible 100

ways to practically construct my device, and that I may make such changes therein as come within the scope of the appended claims without departure from the spirit of my invention.

Having thus described my invention what I claim as new and desire to secure by Letters Patent is:

A device for keeping the sashes of sliding windows and screens apart and locking the same in their relative adjusted positions comprising two telescoping hollow members, one slotted at its lower end, a band guided about this slotted end, oppositely disposed, perforated ears at the inner ends of said band, a screw bolt extending through the perforations of these ears, a head formed at one end of said bolt to limit its movement in one direction and a sleeve and hand wheel carried by the other end of said bolt for allowing a firm squeezing of the slotted lower end of one member about the upper end of the other member telescoping therein, a plug received in the upper end of the upper member and means securing the same therein, a head formed with said plug laterally projecting beyond the outer limits of the upper member at its upper end, a projection on the outer end of said head adapted to engage in a socket on the lower face of a window frame, a base for the lower end of one of said members undercut to form a depending lip adapted to engage the upper bar of a window frame, means for securing said foot on said member, and a rubber cushion on the lower end of said foot.

Signed at New York, in the county of New York, and State of New York, this 17th day of June, A. D. 1930.

40 WALTER BILDSTEIN.
